UNITED STATES PATENT OFFICE.

CHARLES J. TROPPMAN, OF CHICAGO, ILLINOIS, ASSIGNOR TO F. A. HARDY & COMPANY, OF CHICAGO, ILLINOIS, A CORPORATION OF ILLINOIS.

GOGGLES OR EYE-PROTECTORS.

1,261,190.

Specification of Letters Patent.

Patented Apr. 2, 1918.

Application filed October 26, 1917. Serial No. 198,633.

To all whom it may concern:

Be it known that I, CHARLES J. TROPPMAN, a citizen of the United States, and a resident of Chicago, in the county of Cook and State 5 of Illinois, have invented certain new and useful Improvements in Goggles or Eye-Protectors, of which the following is a specification.

My present invention has reference to protectors for the eyes of workmen and others engaged in divers employments, where it is expedient to shade the eyes from bright glare, heat and gaseous emanations of molten metals, acetylene torches, etc., as well as 15 to protect the eyes from flying particles of foreign matter.

Among the objects of my invention is the provision of a goggle or eye-protector that may be constructed without any metallic 20 portions and provided with suitable small slotted openings upon the outer sides of the eye-cups that afford "windows" or sight openings through which the workman is apprised of any danger which may approach from either side and which is not visible within the range of the lenses in the front of the eye-cups. Another object of my 25 invention is the provision of a novel structure for holding the lenses in place in the eye-cups, whereby flying particles of metal or other matter are prevented from lodging in the corners of the lenses and the bezels for securing the same in place, such structure also affording facilities for securing 30 lenses of divers thicknesses in the eye-cups. A further object is the provision of a novel connection between the adjacent peripheries of the eye-cups. And still other objects are the provision of a goggle or eye-protector 35 that is dependable in operation, easy to handle and adjust to the eyes of the wearer, and economical to manufacture.

I prefer to accomplish the divers objects of my invention by the means disclosed in 40 the accompanying drawings that form a part of this specification.

In the drawings—

Figure 1 is a front elevation of a pair of goggles constructed in accordance with 45 my invention.

Fig. 2 is a side view thereof.

Fig. 3 is a fragmental detail, partly in section, of the means for connecting or bridging the eye-cups.

Fig. 4 is a horizontal section of one of the

eye-cups drawn to an exaggerated scale, the section being taken on line 4—4 of Fig. 2.

Fig. 5 is a fragmental view of the eye-cups folded together, face to face, and illustrating the manner of inserting the cup-connecting strap through the slotted ears on the sides of the cups.

Referring to the drawings wherein similar reference characters are employed to designate like parts throughout the views, it 65 will be seen my invention preferably comprises a pair of eye-cups 10, 10, that are flexibly connected together by a suitable ligament 11, of leather, or the like, and are provided with an elastic head band 12, whereby 70 the goggle may be secured to the head of the wearer. The connecting ligament 11 preferably is provided with enlarged ends, as shown, to prevent its accidental removal through the elongated slots 13 made in laterally projecting ears 14, upon adjacent sides of the eye-cups, and in order to readily insert the ligament through these slots, the former is provided with a tapered or pointed portion 15, (as seen in Fig. 5), which is 80 threaded through the slots and by a quick pull is adapted to force one of the enlarged portions through both slots so that this tapered end 15 may be sheared along the dotted line, Fig. 5, after the ligament is in place. 85

The eye-cups are preferably made of a substantially cylindrical shape, the rear edges 16 whereof are shaped to conform to the contour of the face, as shown in Fig. 4 of the drawings, and suitable laterally extended slotted flanges 17 are provided on the edges, opposite ears 14, to which the ends of the head band 12 are secured. Suitable openings or "windows" are provided in the segments of the eye-cup walls adjacent the 95 flanges 17, to afford means for viewing objects at the side of the wearer and out of range of the lens openings of the cups. These sight openings may be of divers types and I have illustrated a single preferred 100 form that consists of a plurality of elongated slots 18, 18, disposed in a horizontal plane parallel with each other and having their end walls converging inwardly toward each other, as shown in the enlarged detail in 105 Fig. 4 of the drawings. The slots of the kind shown, when made relatively narrow, afford the necessary protection to the eyes, as the amount of foreign matter approaching from a lateral direction is not great nor 110

does it have the velocity which is attained by fragments flying directly from the work under observation through the lenses. The narrow slots also are conducive to a clear, if limited, vision on the principle of the stenopaic slots used in testing astigmatism, while the field is increased by the employment of a plurality of slots disposed parallel with each other.

10 A suitable bead 19 is formed adjacent the outer edges of the eye-cups and the portions 10^a of the eye-cups extended beyond these beads are exteriorly screw-threaded to receive internally threaded bezels 20 of the 15 same diameters as the beads against which said bezels are adapted to be snugly fitted. These bezels 20 are preferably of a substantially L-shape in cross-section and the lateral portions thereof are under-cut, as at 20 21 (Fig. 4), in order to make a tight fit with the beveled edges 22 of the lenses 23, that are positioned against the end edges of the eye-cups. The purpose of beveling the edges of the lenses and undercutting the bezels is 25 to accommodate lenses of divers thicknesses, as illustrated by the dotted lines in Fig. 4, and at the same time to avoid a structure having corners extending forward of the lenses and in which particles of foreign 30 matter may lodge. This has been found necessary, as particles impinging upon the lenses which are not permitted to freely glance therefrom, often crack the lenses.

From the above it will be obvious that I 35 have devised a pair of goggles or eye-protectors that meet the requirements of persons employed in work in foundries, making castings, hydraulic press work, acetylene and electric welding and cutting, 40 and the like, and although I have disclosed a single form in which my invention may be constructed, it is obvious the device is capable of modification without materially departing from the principle described. I 45 desire it understood, therefore, that all such changes are freely contemplated within the scope of the appended claims.

What I claim is:—

1. In goggles or eye-protectors an eye-cup 50 of substantially cylindrical shape, a bezel threaded upon the outer end thereof the lens engaging portion of said bezel being undercut, and a lens positioned upon the outer edge of said eye-cup and having a 55 beveled edge adapted to be engaged by the undercut portion of said bezel.

2. In goggles or eye-protectors a pair of

substantially cylindrical shaped eye-cups provided with oppositely disposed slotted flanges and a strip of material flexibly connecting said cups, said strip of material having enlarged portions adjacent its ends of greater dimensions than said slots and having one end tapered to facilitate insertion through said slots and which is adapted to 60 be sheared after the positioning of said strip of material.

3. In goggles or eye-protectors a pair of eye-cups of substantially cylindrical shape and having lenses positioned in their outer 70 ends the walls of said eye-cups provided with horizontally disposed narrow parallel slots whereby the wearer's vision may be directed laterally outside the range of the lenses in the respective cups. 75

4. In goggles or eye-protectors a pair of eye-cups of substantially cylindrical shape having their side walls provided with horizontally disposed openings, bezels threaded upon the outer ends of said eye-cups and 80 having their lens engaging portions undercut, and lenses positioned upon the outer edges of said eye-cups and having beveled edges adapted to be engaged by the undercut portions of said bezels. 85

5. In goggles or eye-protectors a pair of eye-cups of substantially cylindrical shape having their side walls provided with horizontally disposed elongated parallel slots, bezels threaded upon the outer ends of said 90 eye-cups and having their lens engaging portions undercut, and lenses positioned upon the outer edges of said eye-cups and having beveled edges adapted to be engaged by the undercut portions of said bezels. 95

6. In goggles or eye-protectors a pair of eye-cups of substantially cylindrical shape having their side walls provided with horizontally disposed openings, bezels of substantially L-shape in cross-section threaded 100 upon the outer ends of said eye-cups and having their lateral members under-cut, and lenses positioned upon the outer edges of said eye-cups and having beveled edges adapted to be engaged by the under-cut portions of said bezels. 105

Signed at Chicago, county of Cook and State of Illinois, this 19th day of October, 1917.

CHARLES J. TROPPMAN.
